UNITED STATES PATENT OFFICE

110,728

DESIGN FOR AN EMBROIDERED PERFORATED FABRIC SHOE

Henry E. McMahon, Bernard J. Riley, and Michael J. Prandy, Milwaukee, Wis.

Application December 31, 1937, Serial No. 74,016

Term of patent 3½ years

To all whom it may concern:

Be it known that we, Henry E. McMahon, Bernard J. Riley, and Michael J. Prandy, all citizens of the United States and residents of Milwaukee, in the county of Milwaukee and State of Wisconsin, have invented a new, original, and ornamental Design for an Embroidered Perforated Fabric Shoe, of which the following is a specification, reference being had to the accompanying drawing, forming part thereof.

In the drawing:

Figure 1 is a side elevation of an embroidered

perforated fabric shoe showing our new design, it being understood that the perforations extend over the entire upper portions as indicated; and

Figure 2 is a plan view of a portion of the upper material, on an enlarged scale for the purpose of bringing out more clearly the details.

We claim:

The ornamental design for an embroidered perforated fabric shoe, as shown and described.
